UNITED STATES PATENT OFFICE

2,408,942

SCALE

David A. Meeker, Troy, and Kenneth C. Allen,
Dayton, Ohio, assignors to The Hobart Manufacturing Company, Troy, Ohio, a corporation of Ohio

Original application July 8, 1938, Serial No. 218,240. Divided and this application June 29, 1942, Serial No. 448,964

6 Claims. (Cl. 240—2.11)

1

This invention relates to scales, and more particularly to scales of the computing type.

It is a principal object of the invention to provide a scale construction having an outer decorative casing which may be readily removed without affecting the adjustment or setting of the scale, and which effectively seals the scale when in place to prevent access of dust or foreign matter thereto.

It is a further object to provide a simple and effective construction for a sign or advertising display device capable of being changed readily by the user of the scale to display advertising material as desired.

Other objects and advantages will be apparent from the following description, the accompanying drawings, and the appended claim.

In the drawings,

Fig. 1 is a perspective view from the clerk's side showing a scale constructed in accordance with the present invention;

Fig. 2 is a side elevational view within the casing and looking toward the mechanism of the scale, with portions being broken to show the construction more clearly;

Fig. 3 is an end elevational view within the outer casing, and showing the operating mechanism of the scale;

Fig. 4 is a plan view with the platter removed and with portions being broken away to show construction of the sealing means for securing an effective sealing of the outer casing with respect to the scale frame;

Fig. 5 is a detail plan view showing the sign frame device;

Fig. 6 is a sectional view on the line 6—6 of Fig. 5;

Fig. 7 is a detail sectional view on the line 7—7 of Fig. 2, showing the means for fastening the case to the frame of the scale;

Fig. 8 is a view showing the construction of the platter supporting member which provides for sealing the interior of the scale, the platter being in raised or substantially no-load position; and

Fig. 9 is a view showing a modified construction of such sealing means.

This application is a division of parent application 218,240 filed July 8, 1938, now Patent No. 2,287,814, issued June 30, 1942.

Referring to the drawings which disclose a preferred embodiment of the invention, there is shown at 10 a base casting preferably integral and impervious, of generally rectangular shape. A plurality of adjustable feet 11 are positioned

2

beneath the base, having friction pads 12 and being suitably adjustable individually to provide for leveling the scale upon the surface on which it rests.

5 A skeleton framework comprising two end members 14 is bolted to and extends upwardly from adjacent each end of the base 10, both the frame and the base being suitably formed of a lightweight casting and provided with strengthening ribs where desired to impart additional strength. As shown in Fig. 2 at the right-hand end of the scale the frame end member 14 is formed with an outwardly projecting flange 14a above the lever, but is offset inwardly with an 15 inwardly projecting flange 14b where it extends between the chart and the lever, thus providing proper strength while reducing the longitudinal dimension of the scale. A cross member 15 is fastened to the top of the two end members 14, 20 and may suitably comprise a stamping which is bolted to the upper ends of members 14, thereby providing a firm framework support for receiving the scale operating parts.

An outer decorative enameled shell or casing 25 16 is shaped to conform generally with the frame member, and is adapted to be fitted downwardly over the frame, and into sealing relation with the base. This casing does not carry the loads and is not subject to the stresses of the scale, 30 which are carried wholly by the frame. It may be readily placed over the frame and removed therefrom with little possibility of damage to the delicate scale parts being guided by the protecting frame. The casing 16 has a central opening at 17 through which the platter supporting means is received and mounted, and at its lower edge extends into sealing relation with a peripheral flexible strip 18 which is fitted within a groove within the base member 10. The strip 35 tends to project horizontally and upon lowering of the casing into position upon the frame, the lower edge of the casing contacts the flexible strip, bending it downwardly, thereby establishing a highly effective sealing contact around the 40 entire lower periphery of the scale to effectively prevent access of dust, insects or other foreign particles thereto. The casing is fastened to the frame member 15 by means of a pair of screws 20 which are received within an upwardly projecting 45 threaded part 21 fastened to the frame member 15 as by welding or the like. Screw 20 has a tapered head, which receives a flanged washer 22, and a gasket 23 adapted to be drawn down into sealing contact with an upwardly projecting 50 flange 24 formed upon the casing member 16.

Thus when screw 20 is tightened, the casing will be firmly held upon the frame 15, and the attaching means is adequately sealed and protected.

The casing is also formed in its upper part with an opening for receiving grommet 25 which provides a close internal fit with a cylindrical level casing 26, suitably fastened by screws 27 to the frame member 15. Thus the level is not carried by the casing, but is carried by the frame itself and projects upwardly through the grommet in relatively close sealing relation so that again access of dust and the like is prevented, and an effectively sealed condition is maintained in the scale, the casing as described being readily removable upwardly without removal of any of the operating parts.

The frame 15 is curved downwardly as shown at 30 in line with opening 17 in the casing, to provide for receiving the platter support. An annular ring 31 having an inner upstanding flange 32 is fastened to the frame 15 by means of screws 33, the inner diameter of flange 32 being only slightly in excess of that of the member 34 constituting the platter support. As shown in Fig. 8 member 34 has a lower circular rib 34a of slightly larger diameter than the main body of the support, the rib being adapted to closely approach the inner wall of flange 32 in the no-load position of the scale to provide a close seal effectively preventing passage of foreign matter. When a load is placed upon the platform, member 34 moves downwardly, bringing the portion of the body of lesser diameter opposite flange 32, to provide somewhat greater clearance to accommodate the arcuate movement of member 34, the clearance still being sufficiently close to maintain an effective sealed relation. The casing 16 is formed with an annular offset portion 35 and between this offset and the member 31 there is positioned an annular piece of felt or the like 36 which forms a seal between the casing and the frame member. This construction, together with the close clearance of the platter support, completes the sealing construction which provides for maintaining the interior of the scale free of foreign matter.

The platter is shown at 40, as comprising a generally flat plate having an upwardly projecting edge 41 at the customer's side of the scale.

The details of the detachable support for the platter, and the construction of the lever and its associated weighing and chart actuating mechanism, are described in full in said parent Patent No. 2,287,814 and this description is not repeated here.

The charts carry weight indications adapted to be read by the clerk and by the customer, and also carry a series of computed values adapted to be read only by the clerk. For this purpose a reading plate 110 is fastened to the frame members 14 and is provided with an opening 111 therein for cooperation with a series of unit price indications 112 to facilitate the reading of the computed values at the unit prices. A reading line 113 is carried in such position as to be visible through the sight opening 111 in relation to the unit price and the computed value thereof. Member 110 is formed as a continuous uninterrupted plate overlying both halves of the chart, yoke 60 as shown in Fig. 3 passing downwardly beneath plate 110.

A magnifying lens 120 is positioned in line with the reading line 113 and adapted to be used by the clerk in reading the scale and the computed

price valuations. Such magnifying lens is received within a metal frame piece 121 which is formed with inwardly extending lugs 122 adapted to pass through apertures formed in recessed flanges 123 integral with casing 16. When thus positioned in place, the inner end of the lugs 122 is twisted or clamped over, to thereby firmly hold the lens in assembled position. Suitable sealing compound 124 is positioned beneath the peripheral edge of the frame member 121 and the adjacent face of the casing, maintaining a tightly sealed construction. Illuminating means 125 are positioned to direct light upon the chart to enable the same to be read, and are controlled by a switch which causes the lights to be turned on whenever a load is placed upon the platform.

On the customer's side of the scale the computed valuations are of course reversed and not in position to be legible and hence are blocked out by suitable plates making it impossible for them to be seen. However an inverted weight scale adapted to be read by the customer is provided on the chart and a reading device 113A is provided to enable accurate weight readings to be made. It is also desired to provide means on the customer's side adapted to receive an advertising or display device, advertising for instance a special for the day, or any other item to which particular attention is desired to be directed. For this purpose a sheet metal member 130 extends across the width of the scale, being formed with two openings separated by an integral rib 130A, the part 131 adapted to be in line with the weight readings on the scale chart, to provide for reading the actual weight of the material upon the platter. The part 132 is of larger extent, and provides for receiving a suitable advertising display or the like. This construction comprises a Z-shaped flanged member 133 welded to the adjacent inner face of member 130 and having inwardly extending lugs 134 formed thereon and passing through apertures in the casing part 16. A piece of translucent material 135, such as a frosted or ground glass plate is received within the angles of the members 133 and provides for transmitting light from the light source 136, while preventing actually seeing through the plate. Preferably the plate 135 extends beneath both parts 131 and 132, only that portion underlying part 132 being frosted, the remainder being clear. An outer flanged member 137 formed integrally with member 130 is formed with an overhanging lip 138 spaced above the outer surface of the plate 135, leaving a narrow elongated slot therein. Within this slot there is slidably the right angularly bent retaining frame 140, to the underside of which are welded longitudinally extending flat spring members 141 which act to yieldingly retain the frame in proper position while providing for sliding of the frame longitudinally of the slot, to position and remove the same therefrom. Suitable sealing material 142 forms a sealed connection between the body of the casing and the sign assembly. A glass plate 143 is carried by the frame 140.

In the use of the scale, the frame 140 is withdrawn and any desired lettering applied to the glass plate 143 carried thereby. The frame is then replaced in the holder and thus forms a readily changeable sign which may indicate the special for that particular day. Each time the scale is used, illumination of this sign as well as of the adjacent weight reading is effected, and the sign thus stands out clearly, arresting the attention of the customer. A single glass plate 143 is shown

which is adapted to directly receive the lettering in removable paint; if desired however this may take the form of a pair of relatively thin transparent plates between which is received a paper or like strip containing the lettering desired. In such latter case these paper strips may be printed for different products and in different colors, forming a highly attractive advertising device for use in connection with the scale.

Fig. 9 shows a modified construction for sealing the interior of the scale against the access of foreign matter. In this construction the frame is shown at 150, a casing at 151 and a platter supporting member at 152 having a main body portion and a lower circular rib 153 of slightly greater diameter than the body portion. The frame 150 has a series of enlarged apertures 154 therethrough through which extend studs 155 adjustably clamped in place thereon by lock nuts 156. The stud is internally threaded to receive fastening screw 157 which holds an annular flange 158 in place through spring washers 159. The flange is formed with an upwardly offset portion 160 adapted to overlie rib 153 so that in the no load position of the platform, rib 153 will establish close sealing engagement with portion 160, approaching closely though preferably not actually contacting therewith. Should the platter support rise above its no load position, causing rib 153 to strike portion 160, the resilient spring members 159 yield to avoid any deleterious shock to the scale mechanism. In the weighing positions, the scale is effectively sealed, with proper clearance being provided for movement. The construction described provides for accurately positioning the flanged member in proper operating position both laterally and vertically. Felt washer means 161 provides for sealing the outer casing and the frame member to each other.

While the form of apparatus herein described constitutes the preferred embodiment of the invention, it is to be understood that the invention is not limited to this precise form of apparatus, and that changes may be made therein without departing from the scope of the invention which is defined in the appended claims.

What is claimed is:

1. In a scale of the character described having a frame in which there is rotatably supported a drum chart and with an outer casing overlying said frame and said chart and having means for effectively sealing the interior of the scale against access of dust and foreign matter thereto, the casing being provided with a longitudinally extending opening at one side thereof, the combination of a light transmitting member overlying said opening in the casing, part of said member being translucent and part thereof being transparent to provide for viewing a scale on said drum chart, means for mounting said light transmitting member in fixed position in said casing opening, means for sealing said member in position on said casing opening preventing passage of air and dust therethrough, means for illuminating the surface beneath said light transmitting member, a display member, and means on the outside of said casing for removably receiving said display member in position overlying said opening and said translucent part of the light transmitting member while maintaining the entire interior of said scale effectively sealed when said display member is removed.

2. In a scale of the character described having a frame in which there is rotatably supported a drum chart and with an outer casing overlying

the frame and having means for effectively sealing the interior of the scale against access of dust and foreign matter thereto, the casing being provided with a longitudinally extending opening at one side thereof, the combination of a light transmitting member overlying said opening in the casing, part of said member being translucent and part thereof being transparent to provide for viewing a scale on said drum chart, means for

5 sealing said light transmitting member in fixed position in said casing opening, means on the inside of said casing for illuminating the chart beneath the entire area of said light transmitting member, a display member, and means on the 10 outside of said casing for removably receiving said display member in position overlying the translucent part of said light transmitting member while maintaining the entire interior of said scale effectively sealed.

15 20 3. In a scale of the character described having a frame in which there is rotatably supported a drum chart and with an outer casing overlying the frame and having means for effectively sealing the interior of the scale against access of dust and foreign matter thereto, the casing being provided with a longitudinally extending opening at one side thereof, the combination of a light transmitting member overlying said opening in the casing, means for sealing said light transmitting member in fixed position in said casing opening, means for illuminating the chart beneath the entire area of said light transmitting member, a display member including a slide frame and a glass plate adapted to receive display material thereon, and means on the outside of said casing 25 30 35 for removably receiving said display member in position overlying said light transmitting member while maintaining the interior of said casing effectively sealed when said display member is removed.

40 4. In a scale of the character described having a frame in which there is rotatably supported a drum chart and with an outer casing overlying the frame and having means for effectively sealing the interior of the scale against access of dust and foreign matter thereto, the casing being provided with a longitudinally extending opening at one side thereof, the combination of a light transmitting member overlying said opening in the casing, means for sealing said light transmitting member in fixed position in said casing opening, means for illuminating the chart beneath said light transmitting member, a display member including a frame and a plate carried thereby adapted to receive display material, resilient means on said display frame, guide means on the outside of said casing for removably receiving said display frame in position overlying said opening while maintaining the interior of said casing effectively sealed when said display member is removed, said resilient means providing for retaining the frame in assembled position against movement while providing for ready withdrawal thereof.

45 5. In a scale of the character described having a frame in which there is rotatably supported a drum chart and with an outer casing overlying the frame and having means for effectively sealing the interior of the scale against access of dust and foreign matter thereto, the casing being provided with a longitudinally extending opening at one side thereof, the combination of a light transmitting member overlying said opening in the casing, means for sealing said light transmitting member in fixed position in said casing

50 55 60 65 70 75

opening, means for illuminating the chart beneath said light transmitting member, a display member including a retaining frame, a plate for receiving display material carried by said frame, guide means on the exterior of said casing and adjacent said opening for slidably receiving said frame to position said display member in overlying relation with respect to said opening while maintaining the interior of said casing effectively sealed when said display member is removed, and flexible means effective between said frame and said guide for yieldably retaining said frame in assembled position.

6. In a scale of the character described having a frame in which there is rotatably supported a drum chart and with an outer casing overlying the frame and having means for effectively sealing the interior of the scale against access of dust and foreign matter thereto, the casing being provided with a longitudinally extending opening at one side thereof, the combination of a light transmitting member over-

5
